UNITED STATES PATENT OFFICE

SAMUEL G. GREEN, OF GRAY, GEORGIA

MOUNT FOR GUNS

Application filed October 26, 1927. Serial No. 228,899.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

5 The subject of this invention is a mount for guns.

A mount for anti-aircraft guns must possess rapidity of elevation and stability during firing at all angles of elevation. In the type 10 of mount whose movement in elevation is effected by a system of levers for the purpose of securing rapidity of action the requirement of stability is generally not met because the base of the support is abnormally shortened 15 as the gun is elevated.

Accordingly, it is the purpose of the present invention to provide a primary elevating lever which will have a minimum rearward displacement during the first half of its elevation to provide a minimum reduction in the 20 base, and, during the last half of its movement, when the reduction in the base becomes more pronounced, it will be replaced by an auxiliary support which assumes the position 25 of the primary lever at minimum elevation and thereby re-establishes the original base of the support.

With the foregoing and other objects in view, my invention resides in the novel arrangement and combination of parts and in the details of construction hereinafter described and claimed, it being understood that changes in the precise embodiment of the invention herein disclosed may be made within 30 the scope of what is claimed without departing from the spirit of the invention.

A practical embodiment of the invention is illustrated in the accompanying drawing, wherein:

40 Fig. 1 is a view in side elevation of a mount constructed in accordance with the invention;

Fig. 2 is a rear view of Fig. 1.

45 Referring to the drawings by numerals of reference:

There is shown a mount of the pedestal type capable of mounting a pair of guns and consisting of a base 5, a rotatable top carriage 6 terminating at its upper extremity in a pair 50 of spaced arms 7-7 on which is mounted a

cradle 8 by means of the trunnion pin 9. The guns 10, which are shown as of the machine gun class, are rigidly secured by means of pins 10a to the outer sides of the cradle.

The elevating mechanism comprises a system of parallel-motion links including a primary link 11 and an auxiliary link 12 connected at their lower ends to the arms 13 and 13', respectively, fastened to the shaft 18 and at their upper ends to the arms 14 and 15, respectively, secured to or integral with the gun cradle. The primary link 11 is preferably located centrally of the mount while the auxiliary link 12 is disposed at one side thus permitting them to pass each other without interference as the arms and their connecting elements are rocked.

The actuating mechanism for displacing the links is associated with the lower shaft 18 and its arms 13 and 13' and as shown comprises a gear wheel 16 mounted in the top carriage and meshing with a gear 17 on the extended shaft 18 of the bell crank.

As generally indicated by the dotted lines in Fig. 1, when the gun is in position of maximum elevation having been moved through 90° the auxiliary link 12 assumes the initial position of the primary link 11 thus re-establishing the original base line between the trunnion and foremost attachment of the elevating mechanism.

By virtue of the arrangement of the elevating mechanism the gun may be rapidly raised or lowered without impairing its stability and in addition the trunnions may be positioned at the rear of the gun thus permitting the employment of a low mount and facilitating the work of the gunner.

I claim:

1. A mount for guns embodying a support, a gun carrying cradle trunnioned in the support, a pair of elevating links connecting the cradle and support and attached to the cradle equi-distantly from the trunnion axis and in different planes, the forward of said links arranged to have a minimum rearward displacement during the first half of its elevating movement and the other arranged to have a maximum forward displacement dur- 100

ing the same period and actuating mechanism for the links carried by the support.

2. A mount for guns embodying a support, a gun carrying cradle trunnioned in the support, a pair of elevating links connecting the cradle and support, the forward one of said links arranged to have a minimum rearward displacement during the first half of its elevating movement and the other arranged to have a maximum forward displacement during the same period and means for actuating the links.

3. An elevating mechanism for guns embodying a system of links, arms connecting the links, the arms so arranged that one of the links has a minimum rearward displacement during the first half of its elevating movement and the other a maximum forward displacement during the same period, and means for actuating the arms.

4. An elevating mechanism for guns embodying a system of links, and means connecting the links whereby during the first half of elevating movement the links will be so displaced as to cause a minimum reduction in effective base and during the last half of such movement the position of the links will be so interchanged as to reestablish such effective base.

5. In combination with a pivoted member and its support, an elevating mechanism embodying a pair of parallel links, an angular member in the plane of the links and connecting the opposite extremities of the links, one of said angular members associated with the pivoted member, and means for fulcrumming each of the angular members on the support at the point of its angularity.
